UNITED STATES PATENT OFFICE

ANDREW H. NEUREUTHER, OF PERU, ILLINOIS, ASSIGNOR TO WESTERN CLOCK COMPANY, OF PERU, ILLINOIS, A CORPORATION OF ILLINOIS

ELECTRIC DRIVING MECHANISM

Application filed July 5, 1927. Serial No. 203,517.

My invention relates to electrical driving mechanisms and has for its object the production of a driving mechanism for clocks and similar devices whereby an electrical current is used to store up the power or driving force which then utilizes said stored up power to drive the clock or similar mechanism. Its further object is to produce such an electrical driving mechanism in which the usual difficulty due to the destruction or burning of the current connection or switching contact points is entirely eliminated. A further object is to produce such a driving mechanism that is also very economical in the consumption of electrical current by the means of the interrupted current that flows into a condenser which stores the electric energy for giving one impulse to the power storing mechanism and then the discharge of said stored electric energy from said condenser for giving the next or alternate impulse to said power storing mechanism, thus very materially prolonging the time that any given source of electrical power as a dry battery, can operate such a device. It is well known that if the current is allowed to flow continuously (not being interrupted by means of a condenser) that the usual dry batteries immediately polarize and must be renewed frequently to produce the desired operation of the driving mechanism all of which is expensive and rather impractical for clocks and similar mechanisms.

Its further object is to produce such an electrical driving mechanism that will be largely independent of the voltage of the electrical current that supplies the electricity for its operation, and at the same time preventing the burning or destruction of switch or contacting points when said points are connected allowing the interrupted flow of current, or broken to permit the use of the discharging of the condenser current.

A further object is to produce such a mechanism which is very simple in construction, effective, accurate and economical in operation and inexpensive to manufacture.

In the drawings:

Fig. 1 shows a rear view of my electric

clock having the rear movement plate removed.

Fig. 2 shows a top view of my electrical clock showing the electric current charging device in section. 55

Fig. 3 shows an enlarged side view of the current charging device. 55

Fig. 4 shows an enlarged cross-sectional view of Fig. 3 along a line AB and further diagrammatically showing the method of electrically connecting in the condenser, and the electro-magnet with same and the source of electrical power. 60

Similar numerals represent similar parts throughout the several views. In the drawings, 1, represents the front plate and 2 the rear plate of a usual clock movement having the usual main wheel 5 and the spring barrel 6 having a spring 7 one end of which spring 7 connects the arbor of main wheel 5 and the other end with the spring barrel 6. Barrel 6 is mounted on arbor 8 which has a key 9 for the manual winding of the spring 7. Mounted on arbor 8 is a winding ratchet 10 which is prevented from turning backwards by means 65 of a pawl 11 fastened to plate 2 and held into the ratchet by means of the usual ratchet check spring 12 also fastened to said plate 2. Wheel 5 drives the center wheel 4 and as usual the clock gear train as shown. Center wheel 70 80

4 is mounted on its usual arbor 13 which not only carries its usual dial train and hands but a commutator or current changing device which comprises a hub 14 (see Fig. 4) by means of which it is mounted on center arbor 85 13 as shown in Fig. 2. Mounted on arbor 14 but electrically insulated therefrom and from each other by means of the insulating material 15, 16, 17, and 18 shown and indicated are two similarly formed toothed wheels 19 90 and 20 preferably having the same number of teeth and so locked in relation to each other so that the tooth of the one registers with the space of the other, the insulation 18 being interposed between 19 and 20 and of sufficient diameter so it comes very close to the top of the teeth on said members 19 and 20, so that the brush contact member 21 which is mounted on plate 1 touches a tooth on 20 and then a tooth on 19 each one alternately and touch 95 100

the insulation between the contacting with each of the alternate teeth on 20 and 19 respectively so as to avoid short circuiting the current across these teeth, the purpose of 5 which will be further mentioned below.

- Referring to Fig. 4, further, contacting brush 21 is connected to a condenser 22 by means of a wire 23 the other side of said condenser being connected to the electro-magnet 10 24 by means of a wire 25 which electro-magnet is connected to a source of power shown (as is also the condenser and electromagnet) as a battery 26 by means of a wire 27 the other side of battery 26 being connected by a 15 wire 28 to a contacting brush 29 to which is fastened an insulating member 30 which is fastened to plate 1 and contacts with the side of the toothed wheel 20. Fastened on insulated member 30 opposite contact brush 29 20 is a contacting brush 31 which it is evident is always electrically insulated from contacting brush 29. Contacting brush 31 has a wire 32 that electrically connects it with wire 27 at a point in the electrical circuit between 25 the electromagnet 24 and battery 26. From an inspection of the diagrammatic circuits shown in Fig. 4 it is evident that when the tooth of wheel 20 touches the contacting brush 21 the positive electrical current will flow 30 from battery 26 through wire 27, thence through electromagnet 24, then through wire 25 to charge the condenser 22, while the negative current flows through wire 28 then contacting brush 29 thence toothed wheel 20 35 thence contacting brush 21 thence wire 23 to the other side of the condenser 22 until the condenser 22 is fully charged when the flow of current will be stopped. The impulse of current in passing through the electro-magnet 40 24 will as usual energize the electro-magnet causing it to exert an impulsive or pulling movement on its armature to be described below. As the wheel 14 is rotated and contacting brush 21 leaves the tooth on the toothed wheel 20 and engages a tooth on toothed wheel 19 thereby starting the electrical circuit through toothed wheel 19 then contacting brush 31 thence wire 32 thence wire 27 thence electro-magnet 24 then wire 45 25 and the condenser 22 thence wire 23 thence contacting brush 21 and toothed wheel 19. This circuit cuts out the battery 26 but discharges the electrical charge in the condenser 22 which again energizes the electromagnet 24 and causes it to again exert an impulsive 50 pulling movement on its armature as above mentioned. It is evident that because there is no current flowing at the time of making and breaking the contact between the teeth 55 of the toothed wheels 19 and 20 and contacting brush 21 there will be practically no sparking so that these contacts will last indefinitely. It is also evident that because the continuous direct current is used it cannot 60 flow through the condenser so that only a 65

definite (really measured) minimum amount of current is used, making it very economical and enabling the use of the ordinary dry batteries, serviceable with my invention until they become shelf worn instead of from 70 becoming polarized because of the excessive currents generally used in the art previous to this invention.

Fastened on arbor 8 in a gear wheel 33 which engages in a pinion gear 34 mounted on an arbor 35 journaled in plates 36 and 37 which plates are mounted adjacent to and fastened to movement plates 2 and 1 respectively by means of the pillars 38 of the movement shown mounted on the arbor 35 and adjacent to plate 37 is a ratchet wheel 39. A ratchet pawl 40 one end of which engages the teeth on said ratchet wheel 39 is pivotally mounted on plate 37 and is held in engagement with said ratchet teeth by means of the 80 spring 41 shown. Below said ratchet wheel 39 and fastened between said plates 36 and 37 as shown is the above mentioned electro-magnet 24 having pole pieces 43 which electro-magnet is energized by means of the 85 electrical circuits and current as above described. 90

Adjacent to pole pieces 43 is an armature 44 which is pivotally mounted in plates 36 and 37 by means of an arbor 45. Pivotally mounted on one end of armature 44 by means of pin 46 is a pawl member 47 the free end of which engages the teeth of the ratchet wheel 39 and is held in engagement therewith by means of the spring 48 one end of which spring is fastened to said pawl member 47 and the other to the projection 49 on armature 44. Connected to the other end of armature 44 by means of the aperture member 50 is a spiral spring 51 the other end of which is fastened to a threaded member 52 which passes through an aperture in a member 53 fastened between the plates 36 and 37. The nuts 54 are mounted on the threaded part of member 52 below member 53 and regulate the tension of the spring 51. 100

It will be seen that whenever the electro-magnet 24 is energized by either the battery current or the current from the discharge of the condenser, all as above mentioned, and the armature 44 is drawn down to the pole piece 43 that the pawl member 47 will slide over a tooth on the teeth of the ratchet wheel 39, the said ratchet wheel being held in position during this period by means of the pawl 40 as above mentioned. As the armature 44 is drawn toward the pole piece 43 it stretches the spring 51 storing the additional mechanical power in same and which as the current impulse dies away almost instantly exerts said power and force on the ratchet wheel 39 through the pawl member 47 and finally to the spring 7 through the pinion 34 and gear wheel 33 from whence it operates the clock 110 in the usual manner. 115

It will be seen that with the proper num- 120

ber of teeth in toothed wheels 19 and 20 the current impulses can be so regulated that they can be utilized to operate one or more secondary clocks.

5 It is evident that instead of having the clock's driving spring 7 operating the clock at the point shown, it can be attached to any of the arbors closer to the clock escapement, whence considerably less force will be required to actuate the movement.

10 From the above description, it is evident that my electrical driving mechanism is extremely economical and effective in operation, entirely eliminating all difficulty due to the burning and sliding of the contacts so common in these devices previous to my invention.

15 It will be understood of course that while I have here shown one form of my invention, 20 I do not wish to limit myself to the exact form shown but wish to have it taken in a sense illustrative of any or all forms that come fairly within the scope of the appended claims.

25 I claim:

1. In an electric driving mechanism of the type having a condenser associated with an electromagnet for driving clocks, an electric current changing device comprising a rotatably mounted holding means, a plurality of electrically conducting disks each having an aperture and projecting teeth formed integral therewith mounted on said holding means and electrically insulated therefrom and from each other, a conducting member 30 mounted adjacent to each of said disks contacting with the side thereof and a conducting member mounted adjacent to and contacting with said teeth.

35 2. In an electric driving mechanism of the type having a condenser associated with an electromagnet for driving clocks, an electric current changing device comprising a rotatably mounted holding means, a plurality of electrically conducting disks each having an aperture and projecting teeth formed integral therewith mounted on said holding means and electrically insulated therefrom and from each other, a conducting member 40 mounted adjacent to each of said disks contacting with the side thereof and a conducting member mounted adjacent to and alternately contacting with a tooth on each of said disks.

45 3. In an electric driving mechanism of the type having a condenser associated with an electromagnet for winding the driving spring of clocks, an electric current changing device comprising a holding means mounted 50 on one of the arbors of said clock, a plurality of electrically conducting disks each having an aperture and projecting teeth formed integral therewith mounted on said holding means and electrically insulated therefrom and from each other, a conducting member 55

mounted adjacent to each of said disks contacting with the side thereof and a conducting member mounted adjacent to and contacting with said teeth.

4. In an electric driving mechanism of the type having a condenser associated with an electromagnet for winding the driving spring of clocks, an electric current changing device comprising a holding means mounted on one of the arbors of said clock, a plurality of electrically conducting disks each having an aperture and projecting teeth formed integral therewith mounted on said holding means and electrically insulated therefrom and from each other, a conducting member mounted adjacent to each of said disks contacting with the side thereof and a conducting member mounted adjacent to and alternately contacting with a tooth on each of said disks.
